DESIGN FOR A MAGNIFIER READING GLASS

Harold A. Stoltz, Cleveland, Ohio

Application March 16, 1944, Serial No. 112,931

Term of patent 7 years

(Cl. D57—1)

To all whom it may concern:

Be it known that I, Harold A. Stoltz, a citizen of the United States, residing at Cleveland, in the county of Cuyahoga and State of Ohio, have invented a new, original, and ornamental Design for a Magnifier Reading Glass, of which the following is a specification, reference being had to the accompanying drawing, forming part thereof.

Figure 1 is a top plan view of a magnifier reading glass showing my new design.

Figure 2 is a bottom plan view,
Figure 3 is an elevational view of one edge of
the glass, and

Figure 4 is an elevational view of the opposite edge thereof.

I claim:

The ornamental design for a magnifier reading glass, as shown.

HAROLD A. STOLTZ.
